SMOKING ARTICLE

Axel S. Carlson, New York, N. Y., assignor of one-half to Sterner Person, New York, N. Y.

Application June 8, 1946, Serial No. 675,453

5 Claims. (Cl. 131—195)

1

This invention relates to new and useful improvements in smoking articles and has especial reference to pipes and cigar and cigarette holders.

An object is to provide a simple and efficient construction whereby the pipe or device is thoroughly cooled and the smoke is also thoroughly cooled before it reaches the mouth of the smoker.

A still further object is to provide a simple and efficient device whereby the saliva is trapped effectively away from the mouth of the smoker.

Yet another object is to provide a simple and efficient device by means of which the various parts can be quickly and easily taken apart in a few seconds for repair, cleaning, or replacement.

Still another object is to provide a simple and efficient device wherein the smoke travels perforce a very circuitous path so that it is cooled effectively before it reaches the mouth of the smoker and the contained liquids are forced to be deposited therefrom before the smoke arrives at the mouth.

Further and more specific objects, features, and advantages will more clearly appear from the detailed specification hereinafter set forth especially when taken in connection with the accompanying drawings which illustrate several forms which the invention may assume and which form part of the specification.

In brief and general terms the invention includes a plug in one end of the hollow stem provided with upper and lower passages therethrough for the saliva passing through the lower passage and the smoke passing through the upper passage.

Further the invention comprises a plug, a hollow tube extending therefrom to the other end of the stem and opening at each end to the atmosphere whereby the interior of the pipe is subjected to the action of cooling outside air at all times with baffle members disposed along the tube and provided with structure forcing the smoke to travel a circuitous path to move from one end to the other.

Yet further the invention includes a special form of baffle member on a supporting rod or tube within the stem which has an annular peripheral groove forming thin contact rims for engagement with the stem to reduce passage of heat thereto and provide a circuitous path for the smoke together with axial passages in the rims offset from each other to further this circuitous passage of the smoke.

The present preferred forms which the inven-

2

tion may assume are shown in the drawings, of which:

Fig. 1 is a vertical longitudinal section through the preferred form of the device;

Fig. 2 is an enlarged cross section of the left hand portion of a removable member shown in Fig. 1;

Fig. 3 is a transverse section thereof on the line 3—3 of Fig. 2;

Fig. 4 is a vertical longitudinal section through a modification of the device shown in Fig. 1; and

Fig. 5 is a cross section showing the modified parts in an operative position, wherein a cigarette is ejected.

10 In the preferred form of the invention shown in Fig. 1 the invention is adapted for the use of a tobacco pipe and comprises a hollow pipe stem 10 into the wall of which near one end is screwed a pipe bowl 11. A circular block or plug 12 frictionally fits into the end of the stem 10 and has a shoulder 13 to limit the inward movement of the plug into the stem. The outer portion of the plug which extends beyond the end of the stem 10 is of the same diameter as the stem to make a smooth even surface and meeting edge. The plug is provided with an outer axial chamber 14 to frictionally receive the bit 15 of the pipe which has a bore 16 therein leading to the chamber 14. The plug has upper and lower passages 17 and 17' respectively therein, the upper passage being shown in Fig. 1 which connects the chamber 14 with the interior of the stem 10. Through the lower passage 17' the saliva from the mouth of the smoker will pass into the interior of the stem 10 whereas through the upper passage 17 the smoke will pass from the interior of the stem 10 to the chamber 14 and thence out through the bit 15 into the mouth of the smoker.

Extending centrally from the rear face of the 20 plug or block 12 and concentric with the stem 10, is a cooling air tube 18 which may be connected to the plug by being formed integrally therewith or in any other suitable manner. The other end of this tube 18 is screwed into the aperture 19 at the other end of the stem 10. The plug 12 is provided with a lateral passage 20 extending from the one end of the tube 18 to the outer surface of the plug whereby cooling air may pass from the atmosphere at one end of the stem 10 through the tube 18 and out the lateral passage 20 to the atmosphere again.

In order to make the smoke pass in a long circuitous path from the bowl 11 to the bit 15 I have provided a series of separate chambers along the stem in which the liquids in the smoke may

be deposited. These chambers are formed by disposing along the tube 18 a series of disks 21 which may be fitted on to the tube 18 or may be formed or molded integrally therewith as is clear from Fig. 2. Each disk is spaced along the tube from the others and is provided with an annular peripheral groove 22 which forms rims 23 on the disks that make contact with the inner wall of the stem along circumferential regions or areas. In order to pass the smoke from one chamber to the others, the rims of each disk are cut away as at 24 and 25 one rim at point 24 and the other at an opposite point 25 as shown in Figure 2. It can be seen therefore from Fig. 1 that the smoke and contained liquids will leave the bowl 11 pass into the interior of the stem 10 encounter the first disk, pass through the passage 24 thence around the groove 22 to the other passage 25 and thence into the other chamber. From this chamber it passes in the same manner through the next disk and so on until it encounters the plug 12 at which point it passes through the passage 17 or 17' preferably the upper one and thence into the chamber 14 and then into the bit of the pipe and into the mouth of the smoker.

The outside air is constantly circulating through the inner portion of the tube 18 and out the lateral passage 20 and thus tending to cool the smoke. The smoke passes into one chamber and then through and around the circumference of the disks and thus is cooled also by direct contact with the walls of the stem 10. The thin contact of the rims 23 with the stem walls prevent the walls and the stem from being heated too much. The disks 21 act as partitions between the chambers and their annular grooves act as extensions of the circuitous path the smoke is forced to travel in moving from the bowl 11 to the bit 15. In cleaning the pipe, the bit 15 is pulled out and then the plug is turned to unscrew the other end of the tube 18 from the threaded aperture 19 whereupon the plug and the tube with the disks can be pulled out of the stem 10. This leaves a clear uninterrupted passage within the stem which can be thoroughly cleaned and dried. The removed parts can also thus be thoroughly cleaned and dried before being put back into place. In smoking the pipe stem tends to be held in the mouth with a slight downward tilt so that the saliva forming in the bottom of chamber 14 will pass through the lower passage 17' into the interior of the stem. The bowl 11 can also be unscrewed and cleaned separately so that the construction is one in which the various parts are easily and quickly taken apart for the purposes mentioned. It will be appreciated that in cleaning the pipe it is not necessary to soil the hands since by twisting the plug 12 the entire tube 18 may be unthreaded at 19 and renewed as a unit, cleaned and replaced.

In the form of the invention shown in Figs. 4 and 5 the device is modified to act as cigarette holder rather than as a pipe. It will also be seen that this latter form by changing the shape of the end can be used as a cigar holder which naturally would require a more flaring end chamber than for a cigarette.

In this form there is the hollow stem 60 as before, into one end of which a cigarette 26 may be inserted. At the other end the plug 27 is frictionally disposed and is in some respects similar to the plug above described. It frictionally receives the bit 28 having a longitudinal bore 29.

To the inner end of the bit 28 is connected a rod 30 concentric with the stem 60. At the bit end this rod has a passage 31 leading to the bore 29 and a lateral passage 32 extending from the passage 31 to the interior of the stem. At the other end the rod is provided with an enlarged head in the form of a piston 33 fitting slidingly within the interior of the stem 60 and adapted when moved to the right to expel the cigarette 26.

At the right end of the rod 30 it has a passage 34 extending through the head 33 and a lateral passage 35 leading from passage 34 to the interior of the stem 60. On the rod 30 are mounted the same disks 21 as above mentioned with respect to the first form of the invention and they are formed and operate in the same way to force the smoke to pursue a circuitous path through the stem 60.

The plug 27 has an interior chamber 36 in which is housed a compression spring 37 bearing at one end against the inner end of the chamber 36 and at the other end against a shoulder 38 formed on the bit. The spring tends to hold the bit and the rod 30 in a left hand position as shown in Fig. 4 but when the finger presses on the bit it moves the bit and the rod to the right against the pressure of the spring and moves the piston 33 to the right to expel the cigarette or the cigar as the case may be.

The rod 30 at its left portion has a shoulder or flange 39 formed thereon to bear against the rear face of the plug 27 so as to limit the leftward movement of the rod and the bit under the influence of the spring 37.

While the invention has been described in detail and with respect to present preferred forms which the invention may assume, it is not to be limited to such details and forms since many changes and modifications may be made in the invention without departing from the spirit and scope of the invention in its broadest aspects. Hence it is desired to cover any and all forms and modifications of the invention which may come within the language or scope of any one or more of the appended claims.

What I claim as my invention is:

1. A smoking article which comprises a hollow stem, a concentric element extending along the stem inside it, and smoke baffle disks on the element and fitted within the stem, said disks having annular peripheral grooves and offset longitudinal edge passages to permit passage of the smoke through the disks from one end of the stem to the other.

2. A smoking article which comprises a hollow stem, and a baffle disk fitted therein and having an annular peripheral groove and longitudinal passages offset from each other and formed at respectively opposite points in the edges of the disk to permit passage of smoke.

3. A smoking article which comprises a hollow stem, and a baffle disk fitted therein and having an annular peripheral groove forming spaced rims to contact the stem and form a passage for the smoke, said rims having respective longitudinal passages disposed therein at angularly opposite points to allow smoke to pass, and said rims making contact with the inner wall of said stem along circumferential areas.

4. In a smoking article having a stem, the combination of a hollow concentric element mounted within the stem with a plurality of spaced baffle discs fitted on the element, said discs each having an annular peripheral groove forming spaced rims making a passage for the smoke, said rims

having respective longitudinal passages disposed therein at angularly opposite points, and said rims making contact with the inner wall of the stem along their circumferential areas.

5. In a smoking article having a stem, the combination of a hollow concentric element mounted within the stem with a plurality of spaced baffle discs fitted on the element, said element being open at opposite ends to the atmosphere, said discs each having an annular peripheral groove forming spaced rims making a passage for the smoke, said rims having respective longitudinal passages disposed therein at angularly opposite points, and said rims making contact with the inner wall of the stem along their circumferential areas.
